UNITED STATES PATENT OFFICE.

JOHN L. STONE, SR., OF RICHMOND, VIRGINIA.

CUSPIDOR.

1,168,124.

Specification of Letters Patent. Patented Jan. 11, 1916.

Application filed February 13, 1915. Serial No. 8,119.

To all whom it may concern:

Be it known that I, JOHN L. STONE, Sr., a citizen of the United States, residing at Richmond, in the county of Henrico and State of Virginia, have invented certain new and useful Improvements in Cuspidors; and I do hereby declare the following to be a full, clear, and exact description of the invention, such as will enable others skilled in the art to which it appertains to make and use the same.

This invention may be said to relate to spittoons, as that is the use to which I will generally put the finished article; and the object of the same is to produce a receptacle of this kind and probably for this purpose from a single folded blank as of paper or the like and possessing its own or inherent fastening means, herein called a "lock," the whole when set up ready for use having the characteristic features of a sanitary cuspidor and being withal an article of quite tasteful appearance.

A further object is to produce a receptacle of this character which may be stored and shipped in the form of a flat blank of but a single thickness, or which may be set up and then collapsed so that it is quite flat although of smaller contour and several thicknesses.

I do not wish to be limited to the use of this receptacle as a cuspidor, since it may find a variety of uses in many arts, and of course the material and size of parts, as well as their exact configuration, are susceptible of considerable modification. The following specification sets forth the manner in which I construct one of the simpler types of this receptacle, and it includes a few elaborations or amplifications, reference being had to the accompanying drawings wherein:

Figure 1 is a plan view of the blank from which the square shape or type of this spittoon is to be made; Fig. 2 is a similar view after the blank has been bent on the lines shown in Fig. 1, the four corners in Fig. 2 illustrating different stages in the formation and insertion of the lock; Fig. 3 is a perspective view of the finished cuspidor; Fig. 4 is a side elevation thereof; and Fig. 5 is a horizontal section on about line 5—5 of Fig. 3. Figs. 2 to 5 are on the same scale, which is larger than the scale employed in other views. Fig. 6 is a plan view of the

finished cuspidor collapsed or flattened out; and Fig. 7 is a bottom plan view of the same. Fig. 8 is a perspective view of a hexagonal cuspidor made according to my invention, and whose base is as large as the periphery of its top, this view illustrating the addition of certain flaps as will be described; and Fig. 9 is a perspective view taken from the under side of a square type of this cuspidor, wherein the flaps are amplified so as to produce walls which close the otherwise open sides of the receptacle.

Referring now to the drawings, and more especially to Fig. 1 wherein is shown the blank from which a square spittoon is to be made, I have employed solid lines to show folded lines which move downward in shaping up the receptacle, or in other words, where the panels on the opposite side of the solid line move upward; and I have employed dotted lines where the panels move downward and the folded line moves upward. The blank is subdivided into panels whereof the central one B will be the bottom of the article; the panel marked T will be one of four which constitute the top of the receptacle, the four panels marked S, S', S² and S⁴ (the latter being the same as the top panel T) will constitute one of the side walls of the finished article, and finally the two triangular panels marked L, L' will constitute the lock. On this understanding the blank is a square piece of paper bounded by the lines connecting its corners 1, 2, 3 and 4. First I mark the side lines at the points 5, 6, 7 and 8 and then I lay off the panel B which is bounded by the lines connecting the points 9, 10, 11 and 12 and in the present case is a square somewhat less than one quarter the size of the entire blank although this is a matter of choice. If the base of the spittoon is to be comparatively large, the bottom panel will be laid off larger than illustrated. If the base be comparatively small, the bottom panel might be even smaller than illustrated. In any event, however, I would have the corners or angles of the bottom directly opposite points in the periphery which are between the corners of the entire blank, and which in the present instance are shown as midway between the corners, so that each line as 11, 7 from one corner of the bottom to the periphery of the blank will be truly radial, and it will be seen from the following description that this will

110

form the bottom line of what might be called a gutter as indicated by G in Fig. 3. These radial lines subdivide all of the blank around its bottom panel B into four parts or sections in the case of a square cuspidor which we are describing, and as the construction of these sections is identical we need describe but one. Next, finding the center 13 of the bottom B and a radius 14 therefrom to the nearest point 15 in the line around the bottom, I project this radius toward a corner, as 1, to find a point 16 which being connected by lines with the points 9 and 12 produces a triangular panel S^2 of exactly one quarter of the area of the bottom and united therewith by the line 9, 12. I may here say that each panel S^2 forms the lower part of the side of the finished article, as seen in Fig. 4, and as each is exactly one quarter the size of the bottom it follows that when the spittoon is collapsed as seen in Fig. 6 the four panels S^2 flatten out upon the bottom and their apexes 16 overlie the center 13. Next a line is formed from the point 16 to 8, and this with the gutter line G running from 8 to 12 and another line running from 12 to 16 bounds a second side panel S. In similar manner a third side panel S' is formed by lines from 16 to 5, thence to 9, and finally back to 16. In the illustration given the panels S and S' are of the same size as each other and of the same size as the panel S^2 ; but whereas the first two will always be duplicates of each other they are not always duplicates of the inner triangular panel S^2 . That is to say, it will be clear that if the bottom panel B were smaller than herein shown, or larger, the size of the panel S^2 would be changed; whereas if the gutter lines G were longer or shorter so that the amount of stock around the bottom were enlarged or reduced, the size and shape of the panels S and S' would not be the same but they would always be duplicates of each other. Finally, the three triangles S, S' and S^2 will collectively fill the space transversely between any two contiguous gutter lines G, the outer angle 16 of the inner panel S^2 and the inner angles 9 and 12 of the other panels will invariably be the same. These three triangles in the present case are shown as right-angle triangles, but this depends upon the size of the bottom B, as well as the size of the blank around the bottom. If the latter were carried outward to a considerable extent, it is obvious that the line from 16 to 8 would not be parallel with the line 9, 12, and the line from 16 to 5 would also diverge. In the present illustration the line 8, 16 is in alignment with line 16, 5, but this does not always follow. Next the line 9, 16 is carried straight across the blank to the point 17 so as to produce two triangular panels L and L', the former bounded by the lines 8,

16, 17 and the latter by the lines 16, 17, 1. These two triangular "lock" panels will always be duplicates of each other, and in the finished article they overlie each other. In the illustration given, each lock triangle 70 is of the same size as each of the other triangles already described, but this does not follow invariably. The line 8, 16 of the lock panel L forms one edge of the side panel S, and the line 1, 16 of the other lock 75 panel L' forms one edge of the fourth panel S⁴. Therefore, these lines must be of the same length, but the other two edges of each lock panel are susceptible of considerable variation. I may say, however, that when 80 the panel L is the same size as the panel S it will exactly overlie it in the finished article, and the point 17 between the two lock panels will reach completely to the point 12. If the panel L were smaller than the panel 85 S, the point 17 when turned over into the gutter G would fall somewhere between 12 and 8.

The top T is made up of the material which remains between the line 1, 16 and the 90 line 16, 5. When viewed from above as seen in Figs. 3 and 6 this panel forms about one quarter of the top of the cuspidor. When viewed from the side as seen in Fig. 4, this same panel forms one of the panels S⁴ which 95 make up the side of the cuspidor. Therefore it may be said that this remaining piece of the blank constitutes a top panel on its upper face and a side panel on its lower face.

Having laid off the blank with the lines 100 above described, it is next folded as perhaps best seen in Fig. 2. All parts of the blank outside of the bottom are bent upward on the lines 9, 10, 11, 12, which of course creases the blank on the radial gutter lines G. The 105 line 16, 17 between the two lock panels L, L' is then bent upward and carried over to one side as seen at 20 in Fig. 2, and when this is continued around the blank the latter assumes the formation best seen in this view. 110 Each lock, which is now two-ply is then curled slightly as seen at 21, and its extreme corner 27 carried down into the space 28 which overlies the gutter G. The lock is now pushed home, and if the panels L, L' 115 are the same size as the panel S, L will overlie S, L' will overlie L, and when the next section of the blank is folded up L' will lie adjacent to or slightly remote from S' in the next section; and this produces the space 120 28 whose bottom constitutes the gutter G.

The device now assumes the appearance seen in Figs. 3, 4 and 5. The lock panels L, L' have disappeared from sight, having been bent down into the several spaces 28, and 125 yet it is clear that the spittoon will retain this shape without the employment of any extraneous fastening means, because the lock panel L is bent over on the line 8, 16 at such a decided angle, and the apex of the lock lies 130

in the bottom of the gutter G, and the walls of the latter diverge very slightly upward.

When this receptacle is to be used as a spittoon, it is ready for such use at the point 5 to which our description has proceeded; but on the assumption that it is desired to collapse the made-up spittoon into smaller space for purposes of storage, it is only necessary to move two opposite corners in opposite directions so as to give the entire top a partial revolution with respect to the bottom. The spittoon now assumes the shape in top plan view in Fig. 6 and bottom plan view in Fig. 7. In the movement of parts 10 toward this position, each lowermost side panel S² falls upon the bottom B, one panel S' falls inward over said panel S², while the other panel S falls outward away from the panel S² and the remaining panel S⁴ falls 15 onto this panel S. The panel S⁴ is the under-side of the top panel T, so that as the side panels collapse the top panels also collapse and the various points 16 move inward toward each other until finally they directly 20 overlie the center 13 of the bottom B. The composite top T then overlies the remaining side panels, the latter hold in the locks, and everything overlies the bottom; and the aggregate thickness of the collapsed spittoon 25 is only that of a few thicknesses of paper or similar material.

As above suggested, the device could have been stored in its flat or blank form as illustrated in Fig. 1, where its thickness would 30 have been less but its area greater. I presume that in that form it will be stored in warehouses and stores, and shipped by freight or express; but in the collapsed form shown in Figs. 6 and 7 it will be stored in 35 hospitals or at other points of use. However, this is entirely optional with the purchaser, excepting that the devices may be bought cheaper in their flat form and may be stored more readily and opened up for 40 use more quickly in their collapsed form.

In Fig. 8 I have illustrated a few amplifications of which this device is susceptible. It is obvious that the outer edge of each top panel T does not of necessity terminate on a 45 straight line as 1, 5 in Fig. 1, for it might be cut on a curved line as shown at 30 in Fig. 8. This would produce a little flap 31 which I would bend downward on the straight line 1, 5 so as to reinforce the outer 50 edge of the top panel (especially if the latter were large) to give it strength and to prevent it from sagging as it might do if it became moist. I have also made use of Fig. 8 to show that this flap might be made triangular as at 32, and one or both of its outer edges could carry a supplemental flap 33 for ornamental or other purposes. As one of the latter I suggest that when flap 32 stands upright the supplemental flap might be bent 55 back against or possibly gummed to the un-

derside of the side panel so as to hold the flap 32 in its bracing position. I would not be confined in this respect, however, to the necessity for using these flaps mechanically, as it is quite obvious that they could be given 70 a wide variety of shapes for ornamental purposes.

Thus far I have described a collapsible cuspidor wherein no fastening devices or means of any kind was necessary, excepting 75 for the suggestion just made with respect to the supplemental flap 33. Referring now to Fig. 9, it will be observed that the outer edge of the top panel T could be carried beyond the line 1, 5 into a flap so large that 80 we might call it a wall 34, and this wall might be given such shape that it would fill out the contour of the side illustrated in Fig. 4. That is to say, I would carry one side 85 of the wall from point 5 down to 35 (which would be on a line co-incident with the line 5, 9), then I would carry the lower edge of the wall across to the point 36 which would be co-incident with the point 12, and then I would carry the other side of the wall up 90 to the point 1. It is quite within the spirit 95 of my invention to provide means for holding this wall in place, and to this end I have made use of Fig. 9 to show how one side of any wall, as the edge 1, 36 could be continued into a flap 37, over and upon which the other side of the next adjacent wall would be laid, and to which it could be secured as by gumming or otherwise. Attention is now directed to the fact that the 100 four walls 34 constitute what might be called a shell inclosing the open bases of four pyramidal sides, but the lower edges 35, 36 of these walls are not attached to the bottom B. The result is that a receptacle as thus 105 constituted could yet be collapsed by a partial rotary motion as above described, and thereafter the four connected walls could be laid onto the bottom as shown in Fig. 7 by 110 folding them inward on the lines 1, 5 and 115 38 and 5, 39.

I have described and in most cases shown this receptacle as having four sides, I reserve the right to give it any reasonable 120 number of sides, from three upward, and prefer that it be in all cases a geometrical polygon. When the device is used for a cuspidor, its top panels T converge inward and downward and leave open channels or 125 spaces 28, and these stand directly over downwardly and inwardly inclined gutters G. The result is that there is ample opportunity for the sputa to run off any top panel T into the body, where it will be out of sight 130 when the spittoon is viewed from almost any angle. With a spittoon cut from a blank whose bottom has more than four sides, the spaces 28 constitute a star-shaped opening whose arms grow larger toward the center 135

and whose center is sufficiently open for quite a large article, as for instance a half-smoked cigar, and this opening might be enlarged by pressing the points outward, as indicated in Fig. 3 at 40.

What I claim is:

1. The herein described receptacle made from a single blank of pliable material folded on lines defining a polygonal bottom at the center of the blank, and on radial lines from the corners of said bottom to the periphery of the blank dividing the latter into sections around the bottom; each section being folded into a series of panels collectively constituting one side of the receptacle, and into additional panels superimposed on each other and bent into the space between said side and the next and constituting a lock, for the purpose set forth.
2. The herein described receptacle made from a single blank of pliable material folded on lines defining a polygonal bottom within the blank, and on lines from the edge of said bottom to the periphery of the blank dividing the latter into sections around the bottom; each section being folded into a series of panels collectively constituting one side of the receptacle, and into two contiguous triangular panels superimposed on each other and bent into the space between said side and the next and constituting a lock, for the purpose set forth.
3. The herein described receptacle made from a single blank of pliable material folded on lines defining a polygonal bottom at the center of the blank, and on radial lines from the corners of said bottom to the periphery of the blank dividing the latter into sections around the bottom, each section being folded into a series of triangular panels collectively making up a pyramid and constituting one side of the receptacle, and into two triangular panels whose bases are co-incident with one corner line of said pyramid and whose bodies are superimposed and bent into the space between one side of such pyramid and the contiguous side of the next pyramid, for the purpose set forth.
4. The herein described cuspidor made from a single blank of paper folded on lines defining a polygonal bottom at the center of the blank, and folded on lines from the corners of said bottom to the periphery of the blank to define sections around the bottom separated by radial gutters; each section being folded into an inwardly projecting pyramid constituting one side of the cuspidor, and into a pair of triangular panels projecting beyond one corner line of said pyramid and bent down into the space between this pyramid and the next with its outer edge seated in said gutter.
5. The herein described receptacle made from a single blank folded on lines defining a polygonal bottom within the blank, and on radial lines from the angles of said bottom to the periphery of the blank dividing the latter into sections around the bottom; each section being folded into a triangle whose base is co-incident with the adjacent side of the bottom and whose apex is directed outward, into a pair of equal triangles disposed on opposite sides of the first and with their apexes directed inward, into a fourth triangle extending from the base of one of said pair to the periphery of the blank, and into additional panels constituting a lock for holding said triangles out of the plane of the bottom when the receptacle is set up.
6. The herein described receptacle made from a single blank folded on lines defining a polygonal bottom within the blank, and on radial lines from the angles of said bottom to the periphery of the blank dividing the latter into sections around the bottom; each section including four triangular panels folded into a pyramid whose apex is directed inward over the bottom, and means for maintaining the shape and position of such pyramid when the blank is set up.
7. The herein described receptacle made from a single blank folded on lines defining a polygonal bottom within the blank, and on radial lines from the angles of said bottom to the periphery of the blank dividing the latter into sections around the bottom; each section including four triangular panels folded into a pyramid whose apex is directed inward over the bottom, and each section being completed by additional integral panels constituting a lock and bent into the space between one side of this pyramid and the contiguous side of the next.
8. The herein described cuspidor made from a single blank of pliable material folded on lines defining a polygonal bottom at the center of the blank, and on radial lines from the angles of said bottom to the periphery of the blank dividing the latter into sections around the bottom; each section being provided with lines dividing it into six triangles and folded on said lines so that one triangle rises obliquely from the side of the base, two triangles rise vertically from the edges of that named first, the fourth triangle connects the upper edges of the two last named and constitutes one panel of the top of the cuspidor, and the remaining triangles constitute a lock extending into the space between one upright triangle and that next contiguous.
9. The herein described cuspidor made from a single blank of pliable material folded on lines defining a polygonal bottom at the center of the blank, and on radial lines from the angles of said bottom to the periphery of the blank dividing the latter into sections around the bottom; each section being folded on lines into a plurality

of panels, one of which rises obliquely from the side of the base, two others rise vertically from the edges of that first named, the fourth connects the upper edges of the two last named and inclines in a direction opposite to that named first, and the remainder of which panels constitute a lock extending into the space between one upright panel and the contiguous upright panel of the next adjacent section.

10. The herein described cuspidor made from a single blank of paper and folded into a substantially flat bottom and a plurality of sides, each of the latter being a hollow pyramid with its point directed toward the center of the cuspidor, the several points and the side walls of said pyramids being spaced from each other.

11. The herein described cuspidor made from a single blank of paper and folded into a substantially flat polygonal bottom, a plurality of sides, each of the latter being a hollow pyramid with its point directed toward the center of the cuspidor, the several points being spaced from each other and the side walls of contiguous pyramids converging from said points and being integrally united along their outer edges so as to leave spaces between the lines of union and the points, and panels integral with one edge of the upper wall of each pyramid car-

ried over into one of said spaces and constituting a lock.

12. The herein described cuspidor made from a single blank of paper and folded into a substantially flat polygonal bottom, a plurality of sides, each of the latter being a hollow pyramid with its point directed toward the center of the cuspidor, and a flap integral with the outer edge of the upper panel of each pyramid, and bent downward therefrom for the purpose set forth.

13. The herein described cuspidor made from a single blank of paper and folded into a substantially flat polygonal bottom, a plurality of sides, each of the latter being a hollow pyramid with its point directed toward the center of the cuspidor, a wall integral with and depending from the outer edge of the upper panel and shaped to conform with the contour of the base of the pyramid, and a flap projecting from one side edge of said wall for attachment to the opposite side edge of the next contiguous wall, for the purpose set forth.

In testimony whereof I affix my signature in presence of two witnesses.
